(57) **CLAIM**

The ornamental design for an electrical power baton, as shown and described.

DESCRIPTION

FIG. 1 is perspective view of an electrical power baton showing our new design;

FIG. 2 is a front view of an electrical power baton showing our new design;

FIG. 3 is a left side view of an electrical power baton showing our new design;

FIG. 4 is a right side view of an electrical power baton showing our new design;

FIG. 5 is a back view of an electrical power baton showing our new design;

FIG. 6 is a top view of an electrical power baton showing our new design; and,

FIG. 7 is a bottom view of an electrical power baton showing our new design.

The broken lines shown represent unclaimed subject matter and form no part of the claimed design.

1 Claim, 3 Drawing Sheets

FIG. 1

FIG. 7
